UNITED STATES PATENT OFFICE.

GEORGE H. MANN AND ETTA A. MANN, OF ST. JOHNS, MICHIGAN.

HOLDER.

No. 908,292.

Specification of Letters Patent.

Patented Dec. 29, 1908.

Application filed June 9, 1908. Serial No. 437,605.

To all whom it may concern:

Be it known that we, GEORGE H. MANN and ETTA A. MANN, citizens of the United States, residing at St. Johns, in the county 5 of Clinton and State of Michigan, have invented new and useful Improvements in Holders, of which the following is a specification.

This invention relates to holders for the 10 use of seamstresses, and the object of the invention is to provide a simple, cheap and effective device comprising a plate having hooks adapted for the reception of a securing tape by which the device is retained upon 15 the person of the wearer, the plate being provided with a cushion for the reception of pins, a plurality of upturned spaced fingers for holding sewing implements, such as scissors, thimble and a spool of cotton, the plate 20 being also provided with an outturned portion upon one of its sides having a head provided with inclined inner edges adapted to serve as means for holding the thread and having sharpened inner edges for severing 25 the threads when desired.

With these objects in view the invention resides in the novel construction of elements and their arrangement in operative combination, hereinafter fully described and 30 claimed.

In the accompanying drawings, Figure 1 is a perspective view of the device in applied position. Fig. 2 is a front elevation of the same. Fig. 3 is a rear elevation of the same. Fig. 4 is an end elevation of the same. Fig. 5 is a sectional view upon the line 5—5 of 35 Fig. 2.

In the accompanying drawings the numeral 1 designates the improved holder. This 40 holder is preferably constructed of a plate of suitable material having a central or body portion 2 and ends 3 of an approximately greater width than the body. The ends 3 are of an approximately circular formation, 45 and one of these ends is provided with a plurality of annular spaced perforations adapted for the reception of a securing cord by which a cushion 4 is retained upon the device. This cushion 4 may be constructed 50 of any desired material and is adapted for the reception of pins, needles or the like. The ends 3 are both provided with integrally formed rearwardly extending hooks 5, and

these hooks are adapted for the reception of a suitable tape 6 by which the device may 55 be held in position around the neck of a user, as clearly illustrated in Fig. 1 of the drawings. The end 3 opposite the end provided with the cushion 4 has its lower portion provided with a forwardly extending approxi- 60 mately right angular finger 7. This finger or extension 7 is carried forward from the body of the plate a suitable distance and is then bent upwardly in a right angular direction. The vertical portion 8 is provided with a reduced 65 tongue 9, while the portions of the body upon opposite sides of the tongue are bent in opposite directions to provide a rest for a spool of cotton 10. This spool 10 has its central opening positioned upon the 70 tongue 9 as clearly illustrated in the figures of the drawings. The end is also provided with a forwardly extending portion 11 arranged upon its edge at an approximately right angle to the extension 7, and this portion 11 is provided with an enlarged head 12 extending from above and below the edges of the extension. The head 12 is provided with a rearwardly extending portion slightly spaced away from the portion 11 75 and adapted to provide a slot to hold the thread, while the lower portion of the head extends at a slight angle towards the plate 1 and has its inner edge sharpened to provide a cutting face whereby cotton from the 80 spool 10 may be readily severed.

The body portion 1 is provided with a pair of integrally formed loops 13 and 14. The loop 14 is arranged along side the loop 13, and at approximately the center of the 90 plate. The loop 14 is adapted for the reception of scissors or the like, while the loop 13 provides a retaining means of such articles as thimbles, or the like.

Having thus fully described the invention 95 what is claimed as new is:

A holder for the purpose set forth comprising a plate, hooks upon the plate for the reception of a securing tape, loops upon the under edge of the plate, an integrally formed 100 upturned portion upon the under edge near one of the ends of the plate, said upturned portion being provided with a reduced tongue and having oppositely disposed fingers arranged upon opposite sides of the 105 tongue and at right angles thereto, a cushion

upon the opposite end of the plate, and an angular portion provided with an enlarged head having its upper and lower portions extending inwardly towards the plate at an angle towards the angular projecting portion and having one of the edges of this projecting portion sharpened substantially as described.

In testimony whereof we affix our signatures in presence of two witnesses.

GEORGE H. MANN.
ETTA A. MANN.
